UNITED STATES PATENT OFFICE.

FREDERICK ANDREAS, OF ST. LOUIS, MISSOURI.

GAS-BURNER IGNITER.

1,151,327.

Specification of Letters Patent. Patented Aug. 24, 1915.

Application filed July 10, 1914. Serial No. 850,138.

To all whom it may concern:

Be it known that I, FREDERICK ANDREAS, a citizen of the United States, residing at the city of St. Louis, State of Missouri, have 5 invented certain new and useful Improvements in Gas-Burner Igniters, of which the following is a specification.

This invention relates to improvements in gas-burner igniters and has for its object 10 to provide a cheap, efficient, simple, and neat device of the character described, which may be attached to a gas-stove in place of the ordinary cock thereon without changing the design of the front of the stove and the 15 parts thereof or altering the arrangement of the manifold or other feed-pipe, and without making additional holes therein.

A further object of the present invention is to provide an auxiliary igniter of cheap 20 and simple construction whereby an unlighted burner on a gas-stove may be ignited from a lighted burner by merely turning on the cock of the unlighted burner.

Further, the present invention resides in 25 the combination and arrangement of parts described in this specification and set forth in the claims.

In the accompanying drawing forming part of this specification wherein like numbers of reference denote like parts wherever they occur, Figure 1 is a diagrammatical view of a plurality of gas-burners showing the apparatus embodying the present invention in connection therewith; Fig. 2 is a 30 plan view of the igniter of this invention detached from a burner; Fig. 3 is a side elevation of Fig. 2; Fig. 4 is a sectional view on the line 4-4, Fig. 2, showing the device of Fig. 2 connected to a gas-supply pipe and a 35 burner and showing the gas-cock in open position; Fig. 5 is a side elevation of the plug of the cock; Fig. 6 is a perspective view of the auxiliary igniter of this invention; Fig. 7 is a transverse sectional view 40 of the auxiliary igniter and of the part of a burner connected therewith; and Fig. 8 is a diagrammatical view of a plurality of gas-burners, showing an alternate arrangement 45 of the auxiliary igniters.

The device of this invention consists preferably of a plug-cock 1 of the usual construction, except as hereinafter described, said cock having its plug 2 revolvably seated in valve-seat 3 in casing 4 and held in

place therein by any suitable means, such, 55 for instance, as the spring 5 as shown in the drawings. Plug extension 6 is hollow, the hollow portion 7 extending the length of said plug extension and communicating with transverse passage 8 of said plug. Plug 2 60 is so constructed that gas may constantly be supplied to said hollow portion 7 through said plug-cock, this object being preferably attained by means of a groove 9 upon plug 2 from the passage 8 to by-pass port 10, 65 which port 10 communicates with the passage 8, so that when plug 2 is revolved in its seat 3 in the direction of said groove 9 toward and to closed position with reference to the outlet 11 of said cock, gas will continue to flow to said hollow portion along 70 said groove and through said passage 8 and said port 10.

Plug extension 6 bears a perforated pilot-light nipple 12 at the end adjacent to said plug 2, said pilot-light nipple having a perforation 13 communicating with hollow portion 7 and being preferably provided with a regulating means in said perforation, such, for instance, as screw 14 to regulate the 75 flow of gas from hollow portion 7 to pilot-light vent 15, which vent communicates with perforation 13 and directs the flame of said pilot light toward igniter jet 16, which jet is borne by said plug extension and is provided with a perforation 17 for the emission of gas supplied thereto as hereinafter described. Intermediate said igniter jet and said pilot-light nipple, there is preferably a perforated nipple 18, the perforation 19 80 of said intermediate nipple 18 being adapted to issue gas supplied thereto as hereinafter described, the purpose of said intermediate perforated nipple being that gas issuing therefrom may be ignited by said pilot-light 85 thus bridging the flame from said light to gas issuing from said igniter jet. Perforation 19 is preferably relatively smaller than perforation 17 for the reason that it is desirable that only sufficient gas issue therefrom to communicate flame from said pilot-light to said igniter jet, the flame from said igniter jet being necessarily larger for the purpose of this invention hereinafter described. Also, intermediate nipple 18 is 90 preferably shorter than either pilot-light nipple 12 or igniter jet 16 for the purpose, for instance, to facilitate ignition of said 95 100 105

bridging flame by causing the gas issuing from said shorter nipple to cross the path of direction of the flame of said pilot-light.

5 A valve 20 is provided within hollow portion 7 to control the flow of gas to igniter jet 16 and to intermediate nipple 18, said valve 20 and its associated parts being preferably constructed as hereinafter described.

10 A hollow bushing 21 open at both ends, is provided at its inner end with a valve-seat 22, said valve-seat being adapted to seat therein said valve 20 which is preferably a conical valve and which bears a valve-stem 23 extending outward slidably through and 15 beyond the outer end of said bushing 21 and terminates preferably with a button 25 or the like for unseating said valve 20, which valve is normally held in closed or seated position preferably by means of a 20 spring 26 supported in said hollow portion 7 upon shoulder 27 or the like and pressing against said valve 20 when said bushing 21 is in position within hollow portion 7 as hereinafter described. Button 25 or the like 25 provides a convenient means for manipulating said valve to unseat same, and, also, provides a means for limiting the inward motion of valve-stem 23 by striking against a cap 28 or the like with which bushing 21 is preferably provided at its outer end. Valve-stem 23 is preferably constructed of slightly less diameter than hollow portion 29 of bushing 21 from its end adjacent to valve 20 to a point normally slightly within said hollow portion adjacent to the outer end of said bushing, and for the remaining length of said valve-stem to its button 25 the diameter of said stem is of such size as substantially to fill said hollow-portion at 30 the end of said bushing through which said valve-stem is slidably operative, so that when button 25 is depressed and valve 20 is thereby unseated and opened, gas admitted to hollow portion 29 of bushing 21 is substantially prevented from escaping at the outer end of said bushing. Bushing 21 is adapted to fit into hollow portion 7 and to extend therein beyond igniter jet 16 and its 35 perforation 17 and beyond intermediate 40 nipple 18 and its perforation 19, but said bushing 21 must not extend so far into hollow portion 7 as to obstruct the communication of perforation 13 of pilot-light nipple 12 with said hollow portion. To permit 45 perforation 17 of igniter jet 16 and perforation 19 of intermediate nipple 18 to communicate with hollow portion 29 of bushing 21, said bushing is preferably provided with two holes 30 and 31, said holes being adapted to register respectively with perforations 17 and 19 when said bushing is in place in said hollow portion 7, bushing 21 being preferably screwed in place in said hollow portion 7 by means of screw-threads on the in- 50

with screw-threads on the outer side of said bushing 21.

A housing 34 is preferably provided to inclose the assembled parts hereinabove described, said housing being preferably 70 constructed of two vertically divided parts, as shown in the drawing, the edges of one part bearing grooves 35 or the like adapted to engage the adjacent edges of the other part so that when said housing is placed about said assembled parts and screw-bolt 36 or the like is in place for uniting the two parts of said housing, said two parts will be firmly held together. Housing 34 is provided with an appropriate opening 37 75 through which button 25 and the adjacent end of valve-stem 23 preferably extend, and, also, through which opening handle 38 of said plug-cock 1 extends for conveniently operating said plug-cock. Shoulders 39 or 80 the like borne by said opening 37 are preferably provided to limit the movement of handle 38 substantially to prevent its movement beyond full closed position of said cock in one direction and beyond substantially full-open position of said cock in the 85 opposite direction. An opening 40 is provided in housing 34, said opening being adapted to permit egress of flame from igniter-jet 16 for the purpose of this invention, and one or more holes, like holes 41, 90 may be provided in said housing to facilitate the passage of air to flame of said pilot-light and the like within said housing and to assist in keeping said casing and said assembled parts cool. The pilot-light at 95 said pilot-light nipple 12 is protected by said casing so that the very small flame issuing therefrom may not be extinguished by gusts of wind and the like. 100

The above-described device is attached to a gas-stove (preferably at the most frequently used burner thereof) in place of the ordinary cock, such, for instance, as an ordinary plug-cock, and is so constructed that it is not necessary to drill additional holes for its connection to a gas-stove, and, also, its construction is such that the neat appearance of the stove-front is not marred, for the plug-cock bearing the device of this invention above described is constructed so that its handle 38 is substantially in line with the handles of the ordinary plug-cocks on the stove to which this device is attached as shown in Fig. 1. 110

115 For the purpose of illustration, a gas-stove having four burners, 42, 43, 44 and 45 has one burner 42 provided with plug-cock 1 bearing the above-described igniter device of this invention, and the remaining burners 43, 44 and 45 are provided with ordinary cocks 46. For the purpose of conveniently communicating flame from burner 42 ignited by means of the above-described device to an adjacent burner 43, 44, or 45, an auxiliary 120

125 130 interior of said hollow portion 7 co-operating

igniter 47 is provided, said igniter consisting preferably of a hollow tube closed at both ends, there being preferably a spud 48 adjacent each end of said tube, each of said spuds being adapted to fit in opening 49 in said tube and having openings 50 adapted to communicate with the channel of said tube 47. Said tube 47 bears a slot 51 or the like running preferably along the entire length 10 of said tube. The end of one of said spuds 48 protruding from its attached tube 47 is inserted in an appropriate opening 52 therefore in burner 42 and the end of the other spud protruding from that tube to which 15 said spud is attached is inserted in an appropriate opening 52 in adjacent burner 43 and thus the two burners 42 and 43 are connected together by means of tube 47 and communicate with each other through the channel of 20 tube 47, and burner 42 is similarly connected to burner 44 and to burner 45. Flame from ignited burner 42 will ignite burner 43 by means of gas issuing from said burner and flowing toward said flame through tube 47, 25 said flame igniting said gas and traveling along slot 51 of said tube to said burner 43. Similarly, burners 44 and 45 may be ignited.

Instead of connecting the burners of a gas-stove as hereinabove described and illustrated, the burners may be connected in "series" by means of auxiliary igniters 47, as shown in Fig. 8.

The operation of the main igniter device of this invention borne by plug-cock 1, which is connected to burner 42 is as follows: Plug-cock 1 is normally in closed position (shown in the full line position of handle 38 in Fig. 2), with reference to the flow of gas to burner 42, in which position gas is 35 permitted to flow from manifold supply pipe 53 through port 10, groove 9, and passage 8 connected therewith, into hollow portion 7 and out through perforation 13 and vent 15 to feed the flame of the pilot-light 40 ignited at said vent, which flame may be regulated by adjusting screw 14 adapted to regulate the flow of gas through vent 15. When it is desired to admit gas to burner 42, plug-cock 1 is turned by turning handle 38 45 from full line position shown in Fig. 2 to the dotted line position shown in said figure, plug 2 being revolved in its valve-seat 3 in the direction of groove 9 from by-pass port 10 to passage 8 connected therewith, so that 50 during said movement of said plug gas may continue to flow into hollow portion 7 to feed the pilot-light at pilot-light nipple 12. When cock 1 is in open position (shown by 55 dotted line position of handle 38 in Fig. 2) for admitting gas to burner 42, igniter jet 16 will be facing burner 42 in proper position for shooting flame from gas issuing from perforation 17 in the direction of said 60 burner 42. To admit gas into bushing 21, button 25 is depressed to unseat valve 20

and while held in depressed position, gas flowing freely through passage 8 into hollow portion 7 will enter hollow portion 29 of bushing 21 and issue outward through perforation 19 in intermediate nipple 18 and 70 through perforation 17 of igniter jet 16. As gas issuing from intermediate nipple 18 comes in contact with the flame of the pilot-light from nipple 12, said flame being directed toward said intermediate nipple and 75 toward said igniter jet by means of vent 15 as hereinabove described, said gas is ignited and communicates flame to gas issuing with some force through the larger perforation of igniter jet 16, which flame shoots toward 80 burner 42 and ignites gas issuing from said burner, whereupon button 25 is released, valve 20 is reseated in closed position, the flow of gas to said igniter jet and to said intermediate nipple is cut off, the flame 85 from igniter jet 16 and intermediate nipple 18 extinguished while the pilot-light at pilot-light nipple 12 continues to burn.

When it is desired to ignite burner 43 from burner 42 connected therewith by 90 means of auxiliary igniter 47, it is merely necessary to open gas supply cock 46 (of the ordinary construction) to admit gas to its connected burner 43, whereupon flame from 95 ignited burner 42 will travel along slot 51 of tube 47 as gas flows into said tube from said burner 43 and the gas issuing from said burner 43 will be ignited. In a similar manner, burner 44 may be lighted from 100 burner 42, and, also, burner 45 may be lighted from burner 42.

I claim:

1. A gas-burner igniter comprising a casing, a hollow member revolvably seated in said casing and continuously in communication with the gas supply, a pilot-light borne by said member, an igniter jet borne by said member, and a valve controlling the flow of gas to said igniter jet.

2. A gas-burner igniter comprising a movable hollow member, a pilot-light, means to supply gas continuously to said pilot-light, an igniter-jet borne by said member, a valve adapted to control the flow of gas to said igniter-jet, a cock-handle attached to said movable hollow member, and a housing for said member, the said housing bearing means for limiting the motion of said cock-handle.

3. A gas-burner igniter comprising a movable hollow member, a pilot-light borne by said member, means to supply gas continuously to said pilot-light, an igniter-jet borne by said member, a valve adapted to control the flow of gas to said igniter-jet, a cock-handle borne by said hollow member, and a housing for said cock, said housing bearing means for limiting the motion of said cock-handle in two opposite directions.

4. A gas-burner igniter comprising a movable hollow member, a pilot-light borne

- by said member, means to supply gas continuously to said pilot-light, an igniter-jet borne by said member, a valve in said member, said valve being adapted to control the flow of gas to said igniter-jet, a cock-handle carried by said movable member, a housing for said member, said housing having an opening for flame issuing from said igniter-jet, and bearing-means borne by said member for limiting the motion of said cock-handle in two opposite directions.
5. The combination with a gas-burner of a gas-burner igniter, a movable hollow member, a pilot-light borne by said hollow member, means to supply gas continuously to said pilot-light, an igniter-jet borne by said member, and a valve adapted to control the flow of gas to said igniter-jet.
6. The combination with a gas-burner of 20 a gas-burner igniter comprising a movable hollow member, said movable hollow member being in closed position relative to said burner, a pilot-light borne by said movable member, means to supply gas continuously 25 to said pilot-light, an igniter-jet borne by said hollow member, and a valve adapted to control the flow of gas to said igniter-jet.
7. The combination with a gas-burner of 30 a gas-burner igniter comprising a movable hollow member, said hollow member being in closed position relative to said burner, a pilot-light borne by said hollow member, means to supply gas continuously 35 to said pilot-light, an igniter-jet borne by said hollow member, said igniter-jet being adapted to vent toward said burner when said hollow member is moved to open position relative to said burner, and a valve adapted to con-

trol the flow of gas to said igniter-jet, said pilot-light being adapted to communicate flame to gas issuing from said igniter-jet.

8. The combination with a gas-burner of a gas-burner igniter comprising a movable hollow member being in closed position relative to said burner, a pilot-light borne by 45 said movable hollow member, means to supply gas continuously to said pilot-light, an igniter-jet borne by said hollow member, and a valve adapted to control the flow of gas to said igniter-jet, said pilot-light being 50 adapted to communicate flame to gas issuing from said igniter-jet to ignite gas issuing from said burner when said valve is open relative to said burner.

9. The combination with a gas-burner of 55 a gas-burner igniter comprising a movable hollow member, a handle for said movable member, a pilot-light borne by said movable member, means to supply gas continuously 60 to said pilot-light, an igniter-jet borne by 65 said movable member, a valve adapted to control the flow of gas to said igniter-jet, a housing for said movable member, and means borne by said housing for limiting the movement of said handle, said housing having an opening for flame issuing from 70 said igniter-jet in the direction of said burner when said movable member is open relative to said burner.

In testimony whereof I hereunto affix my 70 signature in the presence of two witnesses.

FREDERICK ANDREAS.
